UNITED STATES PATENT OFFICE.

GEORGE HENRY CROKER, OF SEACOMBE, COUNTY OF CHESTER, ASSIGNOR
OF ONE-HALF TO JOHN BLACKWALL CLARK, OF LIVERPOOL, ENGLAND.

MACHINE FOR DELINTING COTTON-SEED.

SPECIFICATION forming part of Letters Patent No. 408,796, dated August 13, 1889.

Application filed March 11, 1889. Serial No. 302,816. (No model.) Patented in England May 24, 1888, No. 7,641.

To all whom it may concern:

Be it known that I, GEORGE HENRY CROKER, a subject of the Queen of Great Britain, residing at Seacombe, in the county of Cheshire, in the Kingdom of England, have invented certain new and useful Improvements in Machines for Delinting Cotton-Seed (for which I have received Letters Patent in England dated May 24, 1888, No. 7,641,) of which the following is a specification.

This invention has for its object to provide an apparatus for depriving cotton-seed of the lint or fiber and external coating which at present are so injurious in the manufacture of cotton-seed cake.

The invention is best described by aid of the accompanying drawings, in which—

Figure 1 is a side elevation of the apparatus, partly in section; Fig. 2, a cross-section 20 on the line *c d*, Fig. 1, parts being broken away; Fig. 3, an enlarged sectional view of the spiral bars, having an abrasive surface and adjacent parts. Fig. 4 is a similar view 25 to Fig. 3 still further enlarged, showing the way in which the coarseness of the abrasive surface is varied from the feed to the tail end of the machine.

In the drawings, *A* is a supporting-frame of any suitable construction, forming a support 30 for the operative parts *B*, a drum, preferably cylindrical, mounted on and fixed to a horizontal shaft *C*, rotating in bearings *C'*, supported by the frame *A*. In the drawings, the shaft *C* is shown horizontal, but in some cases 35 it may be inclined.

The drum *B* consists of circular frames or drums *D*, preferably of metal, mounted on and secured to the shaft *C*, so as to revolve therewith, and wood staves *D'*, which are 40 laid close together and secured to the frames *D* in any desired manner, but preferably by means of bolts or screws. The drum *B* may be made entirely of iron suitably prepared 45 for having card-clothing nailed on it in the manner well understood by those acquainted with textile machinery. The outside surfaces of the staves *D'* are clothed with cards *d*, similar to those used in carding cotton, or 50 with brushes of wire or any other suitable material, which project from the surface of the staves and are firmly secured thereto.

Surrounding the drum *B* and concentric with it I place a skeleton cylinder *E*, formed of steel bars in the following manner: A steel spiral bar *e* of square or rectangular shape 55 passes round and round the drum *B*, and at a short distance from the carding-cloth or brushes *d* on the drum *B*, say a little less than the thickness of cleaned cotton-seed. The pitch of the coils is preferably rather 60 greater at that end of the machine in which the cotton-seed is fed and which has to deal with the seed which is still covered with lint or fiber than it is at the other end where the seed is delivered freed therefrom. At the 65 feeding end we generally make the coils from one and one-half to two inches apart and the delivery end from one to one and one-half inch. Between the threads of the spiral bar *e* one, two, or more bars *e' e'* (according to the 70 pitch of the spiral bar *e* aforesaid) are arranged. They are preferably of a triangular shape, with the apex of the triangle outward and the opposite flat side inward, and their angles do not quite touch either each other or 75 the rectangular spiral bar *e*. The faces of the bars *e'* facing the drum *B* are not quite so close to the surface of the carding-cloth as the faces of the rectangular bars. (See Fig. 3.)

The bases of the bars *e'* facing the drum *B*, and also the sides of the rectangular bar *e*, are cut, preferably, with rasped or file-like teeth, as in Fig. 4, very coarse near the hopper *F*, where the seed, which is covered with fluffy 85 matter, has to be first operated on, but finer and finer as they approach the other end of the machine from which the cleaned seed is delivered. The skeleton cylinder *E* is made in sections, which are jointed together as at 90 *e' e'*, Fig. 2, each section having longitudinal frame-bars *G G*, and an intermediate longitudinal bar or bars *H*, (though the latter are not always necessary,) to which the respective sections of the bars *e' e'* are firmly fixed. The 95 ends of these bars *G H* are secured to curved bars *I*. It may be found equally convenient to divide the skeleton cylinder into two, three, or other number of parts, instead of four.

The sections of the skeleton cylinder or 100 outer casing *E* are fastened together by bolts *g*, which are passed through the longitudinal

frame-bars G G. The cylinder is supported by means of jaws or brackets J, which are secured to the frame A by bolts j^2 and fit over the bars G G aforesaid. The bolts j^2 work in slots j' in the frame A for a reason hereinafter described, and each bracket J is provided with a clamping or tightening screw j , the end of which bears against the bars G G, as shown. By means of the screws j, j^2 and the slots j' the cylinder E may be adjusted concentrically to the drum B, as follows: To adjust it laterally, the screws J^2 of the upper and lower brackets J are slackened off and the adjustment effected by the screws j in the side brackets J, after which the screws j^2 are again tightened up. The vertical adjustment is effected in a reverse manner by slackening off the screws j^2 in the side brackets and operating the screws j in the top and bottom brackets. Each of the sections of the cylinder E being removable, as aforesaid, it is evident that any of the bars e, e' when worn can be separately taken out for repair with very little trouble by simply removing the section which carries them; or the wear of the bars e, e' can be taken up by planing the adjacent faces e^2 of the longitudinal frame-bars G G, so as to reduce the internal diameter of the cylinder E.

30 F is a feed-hopper, preferably provided with a feeding-screw k .

L L' are pulleys; L², a belt, and l a worm and worm-wheel by which the feeding-screw k receives its motion.

35 M is an exit-spout at the other extremity of the machine.

N is a driving-pulley.

The mode of operation is as follows: The cotton-seed is placed in the hopper F, and is fed onto the drum B by the feeding-screw k before the commencement of the triangular bars e' , but between the threads of the rectangular bar e , which commences earlier than the triangular bars e' . The rectangular bar e feeds the cotton-seed forward, and the drum B, whirling round in rapid rotation, keeps on striking the cotton-seed against the rasped edges of the bars, the spiral nature of those bars rapidly causing the cotton-seed to approach the other extremity of the machine. The cotton drawn off the seed by the rasped teeth is blown out between the bars into an outer casing O, and is thus separated from the seed. The seed traveling on gets first cleaned of its fiber, then of its outer rough surface, and in a polished condition leaves the machine through the exit-spout M.

I claim as my invention—

1. In a machine for cleaning cotton-seed or the like, the combination, with an inner rotatable drum provided with a stiff brush-surface, of an outer skeleton abrading-cylinder,

concentric with the said drum, consisting of a spiral bar e in close proximity to the brush-surface, and having its sides cut with rasped or file-like teeth, and of one or more spiral bars e' , alternating with but not quite touching the spiral bar e or each other, arranged with their inturned faces at a suitable distance from the brush-surface and having said faces cut with rasped teeth, substantially as set forth.

2. In a machine for cleaning cotton-seed or the like, the combination, with an inner rotatable drum provided with a stiff brush-surface, of an outer concentric skeleton abrading-cylinder consisting of a rectangular spiral steel bar e , alternating with one or more triangular spiral steel bars e' , arranged with their angles not quite touching each other or the rectangular spiral bar aforesaid, the rectangular bar e having a pitch decreasing as the exit end of the cylinder is approached and its inner face being located in close proximity to the brush-surface, the triangular bars e' having their bases arranged at a suitable distance from the said brush-surface, and provided with rasped teeth gradually decreasing in coarseness toward the exit, substantially as set forth.

3. In a machine for cleaning cotton-seed or the like, an inner rotatable drum provided with a stiff brush-surface and an outer fixed abrading-cylinder formed of a series of approximately-parallel rasped bars e' , arranged circumferentially a short distance apart at a suitable distance from the brush-surface, in combination with a fixed spiral bar e , projecting beyond the abrading-surface of the cylinder into close proximity with the brush-surface, substantially as set forth.

4. In a machine for cleaning cotton-seed or the like, the combination, with an inner rotatable brush-drum B, of the outer skeleton abrading-cylinder E, surrounding said drum and divided longitudinally into sections, each separately removable, the brackets J, supporting said cylinder, and each adjustable in a given direction upon the machine-frame, a bolt-and-slot device j, j^2 , whereby the said brackets may be adjusted, and an adjusting-screw j , journaled in each of said jaws and adapted to adjust the cylinder within the same in a direction at right angles to the adjustment of the jaw, substantially as described.

In testimony whereof I have signed my name to this specification in the presence of two subscribing witnesses.

GEORGE HENRY CROKER.
